BABY SLING

Marjorie M. Stringini, Chicago, Ill.

Application October 27, 1954, Serial No. 32,839

Term of patent 14 years

(Cl. D15—1)

Fig. 1.

Fig. 3.

Fig. 2.

The dotted line showing is for illustrative purposes only.

I claim:

The ornamental design for a baby sling, as shown and described.
